WRIST WATCH STRAP

Joseph Charles Nienaber, Cincinnati, Ohio

Application January 27, 1943, Serial No. 473,710

2 Claims. (Cl. 224—4)

This invention relates to improvements in wrist watch straps and is particularly directed to wrist watch straps made entirely of leather, or other suitable materials.

An object of the invention is to provide a relatively thin and integral end loop for a laminated watch strap which is particularly adapted to receive the strap pin bar of a wrist watch.

Another object of the invention is to provide a leather wrist watch strap having an integral 10 end loop thereon and which has a two-ply thickness throughout its entire length thereby insuring uniform strength and pliability of the strap.

Another object of the invention is to provide a wrist watch strap which is finished on both 15 its sides and which has a two ply thickness throughout its width and length to preclude the penetration of perspiration into the plies and prevent discoloration and deterioration of the strap material and/or wrinkling of the longitudinal edges of said strap.

Another object of the invention is to provide a reliable watch strap made of relatively thin materials and which presents a uniform, pleasing appearance when worn on the wrist and contributes to the comfort of the wearer.

Other objects will become apparent from the following specification and drawing, in which:

Fig. 1 is a top, plan view of my wrist watch strap.

Fig. 2 is a bottom plan view of the strap illustrated in Fig. 1.

Fig. 3 is a plan view of the buckle carrying end of my strap in an opened, flat position.

Fig. 4 is a plan view of the selective buckle receiving end of my strap in an opened, flat position.

Fig. 5 is an enlarged longitudinal section, through the center of my strap shown in Fig. 1, parts thereof being broken away.

Fig. 6 is a fragmental perspective view of the watch pin engaging loop for the strap.

Figs. 7 and 8 are fragmental perspective views of my watch strap in intermediate stages of its construction.

Fig. 9 is a fragmental, perspective view illustrating the manner in which the integral end loop for the strap is cut from a two-ply length of leather.

The numeral 10 indicates a conventional wrist watch which has a pair of spaced ears 11 extending from opposite sides of the watch case for holding a strap engaging bar or pin 12 between them. My watch strap 13 is divided intermediate its ends by the interposition of the

watch 13 into a buckle carrying end 14 and a selective buckle receiving end 15 in the conventional manner. As most clearly indicated in Fig. 4, the selective buckle receiving end 15 of the strap is made from a relatively thin piece of leather stock and is provided with an intermediate body portion 16 and longitudinally extending edge sections 17 and 18 integrally united to and extending transversely from said body portion. The finished side of the leather comprising the body portion 16 is exposed when the strap is being worn on the person and the finished side of the leather comprising the end sections 17 and 18 is in engagement with the wearer's wrist. The longitudinal edge of the unfinished side of section 17 is skived throughout its length as indicated by the numeral 19, while the finished side of section 18 is skived along its longitudinal edge 20. The edge sections are transversely folded 20 upon the body portion along longitudinal fold lines 21 so that the skived edges of the sections meet intermediate the width of the strap in a skived joint 22 (Figs. 2 and 6), an adhesive material being applied to said skived edges to securely fasten said edges together.

As illustrated in Fig. 4, an end flap 23 is formed by the extension of the body portion beyond the adjacent ends 24 and 25 of the edge sections 17 and 18, respectively. The transverse extremity 30 of the flap is provided with a skived portion 26. The end flap is folded back upon itself on line 260 to form a loop 27 for engaging the wrist watch pin, and as shown in Fig. 6, said skived portion 26 overlies and is in engagement with a tapered portion 28 formed in the adjacent edges 24 and 25 of the folded end sections 17 and 18, respectively (Figs. 5 and 6). An adhesive material may be applied between the skived edge 26 and the tapered portion 28 to form an abutting tapered joint 29 between the transverse extremity of the flap and the adjacent edges of the edge sections. A line of stitches 30 secure the flap 23 to the edge sections and to the body portion 16, and a line of stitches 31 may be provided adjacent the edges of the folded watch strap.

A pin engaging loop 32 is formed on the buckle carrying end in a manner similar to that described on the selective buckle receiving end 15, said loop being provided by a flap 33 on the intermediate body portion 34 which extends beyond the adjacent edges 35 and 36 of edge sections 37 and 38, respectively. A buckle loop 39 is provided for the strap by a flap 40 which is formed by the extension of the body portion 34 beyond the ad-

adjacent edges 41 and 42 of the edge sections, the extremity of said flap 40 being tapered at 43 to engage and overlie a beveled portion 44 formed on the adjacent edges 41 and 42 of the edge sections when they are in folded position. A ring-like keeper 45 is held between the folded flap by means of two lines of stitches 46 and 47 which secure the flap together on either side of said keeper. A line of stitches 48 may be positioned adjacent the longitudinal folded edges of the strap.

The method of manufacturing the wrist watch strap illustrated in Figs. 1-6 consists in cutting an elongated strip 49 from a piece of thin leather stock, said strip having a transverse dimension larger than the width of the finished two-ply strap to provide for an overlapping longitudinal joint disposed intermediate one of the plies. As shown in Fig. 7 opposed longitudinal edges of the strip are then provided with tapered edges which are cut in opposite surfaces of the strip, the tapered edge 50 being formed in the unfinished surface 51 of the leather strip and the tapered edge 52 formed in its finished surface 53. An adhesive material is then applied to both of said tapered edges and the strip is then formed into a tubular shape 54 by bringing the tapered edges into spaced relationship (Fig. 8). In this tubular shape the finished surface 53 forms the exterior surface of the tube and the tapered edges 50 and 52 extend longitudinally thereof. The tube is then run into a pressing device and flattened into a two-ply sheet 56 shown in Fig. 9 with the tapered edges in abutting and overlying relationship, said pressing operation forming a secure joint 22 between said edges. It will be noted that the longitudinal joint 22 is disposed intermediate the folded edges 57 of the sheet during this pressing operation.

The sheet 56 is then cut into suitable watch strap lengths and the proper ends of each length are provided with loops for engaging the watch pin bar or the buckle of the completed strap. These loops are formed as indicated in Fig. 9 by making a diagonal, transverse cut 58 through the ply 59 having the joint 22 therein, and from the inner edge of said diagonal cut, the cutting operation is continued outwardly to the end of said length on a horizontal line 60 thus cutting the portion 61 of the ply 59 from the length. The transverse extremity 62 of the ply 63 is then skived and said extremity is folded back upon itself so that the skived portion thereon is in

abutting relationship with the tapered ends of ply 59 made by the cut 58. Adhesive material and then a line of stitches is applied to form a secure joint 29 (Fig. 6) between the skived transverse extremity of the ply 63 and the tapered portion of the ply 59 formed by the cut 58.

What is claimed is:

1. As an article of manufacture, a two part wrist watch strap each constructed from a single thickness of leather having finished and unfinished sides and each part comprising a longitudinally extending, intermediate body portion, foreshortened edge sections folded transversely upon the unfinished side of the body portion, the said sections having longitudinally extending tapered edges disposed in abutting relationship in said folded positions, the finished sides of the sections forming the interior, wrist engaging side for the strap part, tapered transverse ends on the edge sections, an end flap formed by the extension of the intermediate body portion beyond the said tapered ends of the edge sections, said end flap being folded back upon itself to form an integral watch pin engaging loop, a tapered transverse extremity on the flap overlying the tapered ends of the sections and disposed in abutting relationship therewith, means for securing the flap extremity to the edges of the sections, and means on the free ends of the strap parts for securing the strap to a wrist.

2. As an article of manufacture, a two part wrist watch strap each constructed from a single thickness of leather having finished and unfinished sides and each part comprising a longitudinally extending, intermediate body portion, foreshortened edge sections folded transversely upon the unfinished side of the body portion, the said sections having longitudinally extending edges disposed in abutting relationship in said folded position, the finished sides of the sections forming the interior, wrist engaging side for the strap part, transverse ends on the edge sections, an end flap formed by the extension of the intermediate body portion beyond the said ends of the edge sections, said end flap being folded back upon itself to form an integral watch pin engaging loop, the transverse extremity of the strap being in abutting relationship with the ends of the sections, means for securing the flap extremity to the intermediate body portion, and means on the free ends of the strap parts for securing the strap to a wrist.

JOSEPH CHARLES NIENABER.
